UNITED STATES PATENT OFFICE

HARRY L. BLOME, OF STONINGTON, ILLINOIS

THERMOSTATIC ALARM

Application filed March 21, 1930. Serial No. 437,918.

This invention appertains to new and useful improvements in electrical signalling, and more particularly to a novel thermostatic alarm for warning persons of an exceeding 5 high or low temperature in a brooder or other place requiring an even constant temperature.

The principal object of this invention is to provide a thermostatic alarm including a thermostatic switch constructed in such a 10 manner as to not be susceptible to the development of ready defects.

Other important objects and advantages of the invention will readily become apparent to the reader as the specification proceeds hereinafter.

In the drawings:—

Figure 1 represents a bottom plan view of the novel thermostatic switch.

Fig. 2 represents a side elevational view 20 of the switch and the electrical connections between the same and the source of current and annunciator.

Referring to the drawings wherein like numerals designate like parts, it can be seen 25 that it is preferable that the thermostatic switch include a panel or some other suitable plate 5 of di-electric material. To the bottom side of this plate 5 are secured the spring arms 6, 7 and 8, each of which has a horizontally disposed portion which is referred 30 to respectively by numerals 9, 10 and 11.

The horizontal portions 9 and 11 are provided with contacts 12 on the opposed sides 35 hereof, each in opposition to a contact 13 on the opposite side of the horizontal portion 10 of the arm 7.

These arms 6, 7 and 8 are secured to the panel 5 by bolts 14 and nuts 15. The panel 40 5 has an opening 16 therein in which engage the internally threaded bushings 17, through which the screw 18 is feedable. This screw is provided with a head 19 at its upper end and is secured at its lower end to the thermostatic wafer.

The lower end of the spring arm 7 is secured to the under portion of the wafer 20 as at 23. The free end of the horizontal portion 11 of the arm 8 is bent backwardly as 50 at 24, and the nut 25 is interposed between

this portion 24 and the opposed portion of the horizontal part 11 of the arm.

The threaded stem 26 depending from the panel 5 extends through the nut 25 and is provided with a head 27 at its lower end to 55 limit the extent of travel of the nut 25.

Obviously, by feeding the nut 25 upwardly or downwardly, the contact 12 on the horizontal portion 11 of the arm 8 may be suitably spaced from the contact 13 of the 60 arm 7. The proper adjustment of the horizontal portion 10 of the arm 7 may be made through the adjustment of the screw 18.

In this manner, the device is adjustable throughout to accommodate the same to a 65 wide range of temperatures. As is clearly shown in Fig. 2, the battery 28 has a lead 29 extending through the switch 30 to the arm 7, while both the arm 6 and the arm 8 are connected by the common wire 31 to one side 70 of the annunciator 32, the opposite side of the annunciator or alarm being connected by the wire 33 to the negative side of the battery.

Thus, when the switch 30 is closed, a pre-determined temperature variation will result 75 in the engagement of the contact 13 with either the contact on the arm 6 or the contact on the arm 8, in either case, resulting in the completion of the alarm circuit and the sounding of annunciator 32.

While the foregoing specification sets forth the invention in specific terms, it is to be understood that numerous changes in the shape, size and materials may be resorted to without departing from the spirit 85 and scope of the invention as claimed hereinafter.

Having thus described my invention, what I claim as new is:—

1. A thermostatic switch comprising a support, a thermostatic element on the support, a contact arm carried by the thermostatic element, a stationary contact strip having one end secured to the support, a threaded protuberance on the support, the opposite end 90 of the contact strip being provided with a U-shaped formation, the opposed portions of the U-shaped formation being provided with registering openings through which the threaded protuberance extends, and a nut on 95

100

the threaded protuberance between the apertured portions of the contact strip.

2. A thermostatic switch comprising a support, a thermostatic element on the support, a contact arm carried by the element, a contact strip having one end secured to the support, the opposite end of the contact strip being provided with an opening, a threaded protuberance on the support extending through the opening in the contact strip, and a nut seatable on the threaded protuberance for urging the contact strip at its free end in a given direction.

10
15 In testimony whereof I affix my signature.
HARRY L. BLOME.
